COMBINED AUTOMOBILE DASHBOARD AND STEERING WHEEL TOY

Albert Stubbmann, Flushing, N.Y., assignor to Kohner
Bros., Inc., New York, N.Y., a corporation of New York

Filed July 17, 1964, Ser. No. 80,917

Term of patent 7 years

(Cl. D34—15)

FIG. 1 is a front elevational view of a combined automobile dashboard and steering wheel toy showing my new design;

FIG. 2 is a top plan view thereof;

FIG. 3 is a left side elevational view thereof;

FIG. 4 is a rear elevational view thereof;

FIG. 5 is a bottom plan view thereof; and

FIG. 6 is a right side elevational view thereof.

I claim:

The ornamental design for a combined automobile dashboard and steering wheel toy, substantially as shown.
